AUTOMATIC CHOKE

Glen R. Sisson, Pendleton, Ind.

Application February 17, 1933, Serial No. 657,244

1 Claim. (Cl. 123—179)

My invention is concerned with automatic control of the proportions of the mixture produced in the carburetor of an internal combustion engine. It is the object of my invention to produce a device which will automatically control mixture proportions in accordance with temperature, which will provide a temporary enrichment when the engine is being cranked, which will not interfere with satisfactory performance of the engine under either wide open or closed throttle, which can be simply and economically constructed, and which may be very easily installed.

In carrying out my invention, I provide the carburetor with a choke-valve of the butterfly type which is eccentrically pivoted so as to tend to swing toward open position under the influence of air which passes it, and I provide for this choke-valve a yielding temperature-responsive loading element which yieldingly opposes opening movement of the choke-valve under the influence of the air flowing past it. The control of the choke-valve effected by the temperature-responsive loading element is supplemented by two mechanisms one of which is operable when the engine is being cranked to prevent movement of the choke-valve under the influence of the air flowing past it and the other of which is controlled jointly with the throttle valve to limit to a predetermined extent the choking effect produced at open and closed throttle positions.

The accompanying drawing illustrates an embodiment of my invention: Fig. 1 is a somewhat diagrammatic showing of an engine equipped with a mixture-control device embodying my invention; Fig. 2 is a horizontal section through my device on the line 2—2 of Fig. 3; and Fig. 3 is a front elevation of the device with parts thereof broken away.

Indicated diagrammatically in Fig. 1 are the inlet and exhaust manifolds 10 and 11 of an internal combustion engine, a carburetor 12 connected to the inlet manifold 10, an electric engine-starting motor 13, a battery 14 for supplying electrical energy to the motor 13, and a starter switch 15 through which the motor 13 may be connected to the battery 14. The carburetor 12 is shown as provided with the usual throttle valve 16 and a choke-valve 17 mounted in the air-inlet opening 18 of the carburetor 12.

The choke-valve 17, as is clear from Fig. 1, is pivoted on an eccentric axis in the carburetor-inlet passage 18, whereby the flow of air past it tends to swing it toward open position. For the purpose of controlling the extent of the opening movement of the choke-valve, I provide a tem-

perature-responsive element which is responsive to engine temperature and which permits the choke-valve to approach wide-open position as the engine temperature increases.

As shown in the drawing, the temperature-responsive element just referred to comprises a spirally coiled bimetallic strip 20 the outer end of which is fixed to a housing 21 mounted on the side of the exhaust manifold 11 and the inner end of which is secured to a rotatable shaft 22 supported from the housing 21. Mounted on the outer end of the shaft 22 is an arm 23 connected through a link 24 to the choke-valve 17. The parts are so arranged that as the temperature adjacent the exhaust manifold 11 increases the shaft 22 is rotated in a clockwise direction (Figs. 1 and 3), thus raising the link 24 and moving the choke-valve 17 toward open position.

I have referred above to mechanism for preventing opening movement of the choke-valve 20 during any period in which the engine is being cranked to start it. Conveniently, this mechanism is in the form of an electro-magnetic brake for the shaft 22, such brake being connected in parallel with the starter-motor 13.

As shown in Fig. 2, this electro-magnetic brake comprises a cup-shaped member 30 of magnetic material and a central hub-like member 31 associated therewith and also made of magnetic material. The two members 30 and 31 constitute the pole pieces of an electro-magnet winding 33 which surrounds the member 31 within the flange of the cup-shaped member 30. The two pole pieces 30 and 31 are outwardly directed, and immediately beyond them on the shaft 22 there is secured a disk 34 of magnetic material which constitutes the armature of the electro-magnet.

A cover 36, the inner end of which fits over the cylindrical housing 21, encloses the electro-magnet and the disk 34 and provides a support 40 for the outer end of the shaft 22. The shaft 22 is not only rotatable in its support but is also axially slidable through a distance sufficient to permit the armature to move into and out of engagement with the pole piece 30. The resiliency of the bimetallic strip 20 serves normally to hold the armature 34 out of engagement with the pole piece 30; but when the electro-magnet 33 is energized, the armature 34 and shaft 22 will be 50 drawn inwardly, causing the bimetallic strip to be drawn to the dotted-line position indicated in Fig. 2. Upon de-energization of the electro-magnet 33, the bimetallic strip 20, as the result of its resiliency, will be returned to its normal 55

plane and will carry the shaft 22 and armature 34 outwardly.

As is clear from Fig. 1, the electro-magnet 33 is connected in parallel with the starter motor 13 so as to be energized whenever the starter motor is operative. Therefore, when the starter-motor switch 15 is closed, the magnet 33 is energized and draws the armature 34 inwardly into contact with the pole-piece 30 thus braking the shaft 22 and preventing air flowing past the choke valve 17 from moving it toward open position beyond that position in which it was held by the temperature-responsive element 20 before the starter switch 15 was closed. When the engine begins to operate under its own power and the starter motor switch 15 is opened, the magnet 33 is de-energized, thus permitting the armature 34 and shaft 22 to move outwardly. This relieves the braking effect and permits the choke-valve 17 to swing toward open position under the load imposed by the temperature-responsive element 20. This movement of the choke-valve produces a decreased enrichment of the mixture; and as the engine-temperature increases, the temperature-responsive element 20 continues to move the choke-valve toward open position until when normal operating temperature of the engine is attained the choke-valve will be completely open.

I have found that it is desirable to impose upon the choke-valve control afforded by the temperature-responsive element 20 and the electro-magnet 33 a further control in accordance with throttle-position. This additional control limits the choking effect at both closed-throttle and open-throttle positions. The former I find especially desirable to prevent too great a choking effect as the result of the low-air-velocity past the choke-valve when the throttle is closed, and the latter is advisable to prevent the choke-valve from unduly restricting air-flow through the carburetor at wide-open throttle.

To effect control of the choke-valve in accordance with throttle-position, I provide on the disk 34 two outwardly projecting abutments 40 and 41 which co-operate respectively with inwardly extending pins 42 and 43 secured on opposite sides of the pivotal axis of an arm 44 pivotally mounted on the outside of the cover 36 and connected to the throttle-valve 16 by means of a link 45. Choking movement of the shaft 22 is limited by the co-operation of the two pairs of abutments 40-42 and 41-43.

Figs. 1 and 2, and Fig. 3 in full lines, indicate

the condition of the device at intermediate throttle position and with the engine cool. The parts are so arranged that as the throttle is closed the arm 44 is swung upwardly to lower the pin 42 toward its association abutment 40 on the armature 34. Further, the relative locations of the abutments 40 and 41 and the pins 42 and 43 are such that when the throttle is near the mid-point of its range of adjustment the pins 42 and 43 do not interfere with complete closing of the choke-valve. Upon extreme closing movement of the throttle, however, the arm 44 is swung upwardly to a point near the upper dotted-line position shown in Fig. 3, thus lowering the pin 42 to such an extent that it will be engaged by its associated abutment 40 to limit closing movement of the choke-valve short of completely closed position. Similarly, when the throttle is moved to its extreme open position, the arm 44 is lowered to the lower dotted-line position illustrated in Fig. 3, and the pin 43 swings downwardly with it to co-operate with the abutment 41 in preventing the choke-valve from being completely closed.

By reason of the construction just described, it will be apparent that if the engine is running either under completely closed or completely open throttle the choke-valve can not be completely closed.

In order to prevent the abutment 40 and pin 42 from preventing complete closing movement of the choke-valve during cold starting should the throttle be closed, the pin 42 is made short enough so that the abutment 40 will pass out of engagement with it as the armature 34 and shaft 22 are drawn inwardly when the electro-magnet 33 is energized. The pin 43, on the other hand, is long enough to remain in engagement with its associated abutment 41 on the disk 34 under all conditions, and thus it is always possible, by moving the throttle to wide-open position, to open the choke-valve and correct any tendency of the device to cause flooding of the carburetor.

I claim as my invention:—

In combination with an internal combustion engine having a carburetor provided with an unbalanced choke-valve, a rotatable shaft connected to said choke-valve to operate it, a temperature-responsive element for rotating said shaft, a brake associated with said shaft, and mechanism operative during cranking of the engine for actuating said brake.

GLEN R. SISSON.
